UNITED STATES PATENT OFFICE

172,270

HOLDER FOR RAZORS AND BLADES

Christy M. Del Mas, New York, N. Y., assignor to Michael P. Grace, New York, N. Y.

Application May 4, 1953, Serial No. 24,836

Term of patent 14 years

(Cl. D80—9)

To all whom it may concern:

Be it known that I, Christy M. Del Mas, a citizen of the United States of America, residing at [redacted], county, and State of New York, have invented a new, original, and ornamental Design for a Holder for Razors and Blades, of which the following is a specification, reference being had to the accompanying drawing, forming part thereof.

Figure 1 is a perspective view of a holder for razors and blades embodying my new design, and Figure 2 is a top plan view thereof reduced.

I claim:

The ornamental design for a holder for razors and blades, as shown.
